ELECTRIC COUPLING SYSTEM

Application filed July 14, 1928, Serial No. 292 739, and in Great Britain July 2, 1926.

This invention relates to electric coupling systems especially adapted for use with radio-frequency vacuum tube amplifiers, and more particularly to circuit arrangements which operate most effectively over a relatively wide range in frequency. Such systems are discussed more generally in my copending application for U. S. Letters Patent Serial No. 120,045, filed July 2, 1926, of 10 which the present application is a continuation in part; Figs. 2 and 5 of this present application being the same as Figs. 6 and 8 of the prior application, and present Fig. 1 being the same as prior Fig. 2 except for 15 the substitution of a radio-frequency self-inductance for the choke coil described in the prior specification.

The mentioned prior application discloses various forms of coupling systems so arranged as to give a voltage ratio that varies automatically with the frequency. The present application is confined to such coupling systems in which the variation in voltage ratio is accomplished in a primary circuit 25 which includes a fixed self-inductance effectively in parallel with one or more fixed capacities external to the main resonant circuit and which may be electrically isolated from the main resonant circuit. The primary 30 circuit is resonant at a frequency lower (but preferably not greatly lower) than the lowest frequency within the range of the coupling system.

The voltage ratio in an inter-tube coupling 35 system affects the degree of amplification, the stability and the selectivity. At each frequency there is a particular ratio of output voltage to input voltage that will give the best compromise design. This ratio varies rapidly with the frequency, being relatively high at high frequencies. This invention provides means for securing substantially the most desirable ratio at all frequencies without having any adjustable element except the tuning adjustment.

Referring to the drawings, Fig. 1 illustrates a vacuum tube and an electric coupling system embodying a simple form of this invention.

Fig. 2 illustrates a modification of Fig. 1 having an additional fixed capacity.

Fig. 3 illustrates a modification of Fig. 2 in which a two-coil transformer replaces an auto-transformer.

Fig. 4 illustrates a modification of Fig. 3 by which direct voltage is removed from the fixed capacities.

Fig. 5 illustrates a form of this invention in which a self-inductance coil (L_3) of the preceding figures, is electromagnetically coupled to the transformer.

Fig. 6 illustrates a modification of Fig. 5.

Fig. 7 illustrates another modification of Fig. 5.

The coupling system of Fig. 1 is tuned by a variable condenser C_2 connected across the primary coil L_1 and the secondary coil L_2 in series. Ordinarily L_1 should have much fewer turns than L_2 so that there is a high step-up voltage ratio between them. The path through the primary coil L_1 from the plate of the vacuum tube to the filament includes also the fixed capacity C_5 which is external to the main resonant circuit C_2, L_2, L_1 . In parallel with this path is a second path including the self-inductance L_3 , the value of which is so chosen that its circuit (completed through C_5 and L_1) is resonant at a frequency lower, but not greatly lower, than the lowest frequency within the range of condenser C_2 .

The circuit of L_3 , being completed through C_5 and L_1 , is thereby coupled to the main resonant circuit C_2, L_2, L_1 ; so that part of the current of C_2 and L_2 will flow through C_5 and L_3 , this part of the current being limited mostly by the reactance of L_3 . Since the reactance of L_3 varies directly with the frequency while that of C_5 varies inversely with the frequency, the voltage across C_5 will rapidly fall off relative to the voltage across L_1 as the frequency rises. For a given output voltage E_2 , the voltage across L_1 is very nearly independent of frequency, due to the electromagnetic coupling between L_1 and L_2 . Hence the voltage E_1 between the plate and the filament, being the sum of the voltages of C_5 and L_1 , will fall off relative to E_2 as the frequency rises, but less rapidly than the

voltage across C_5 alone. This is the condition which is desired and which results in the maintenance of a high degree of stability over the frequency range, together with high sensitivity and selectivity.

5 The operation of the circuit of Fig. 2 is essentially the same as that of Fig. 1, but here the circuit of L_3 is completed through two parallel paths, that through C_3 and that through C_5 and L_1 . As before, this circuit 10 L_3 , C_3 , C_5 , L_1 should be made resonant at a frequency lower, but not greatly lower, than the lowest frequency within the range of C_2 . As described in the above-mentioned prior 15 application, the voltage ratio E_2/E_1 in Fig. 2 is obtained from a double step-up, first between C_3 and the combination of C_3 and C_5 , and then between L_1 and L_2 ; and, with the 20 resonant condition just given, this voltage ratio will automatically vary with the frequency in the same manner as in Fig. 1.

Fig. 3 differs from Fig. 2 only in that the primary coil L_1 is not included in the main resonant circuit. Coil L_1 should here have 25 the same number of turns as in Fig. 2; while the secondary coil L_2 should have the same number of turns as L_1 and L_2 , combined, in Fig. 2. The remaining relations are the same as in Fig. 2.

30 In Fig. 3 the direct voltage of the plate battery B exists across condensers C_3 and C_5 , which is disadvantageous in that these condensers may break down. This difficulty is obviated in Fig. 4 by connecting the lower 35 terminals of condenser C_3 and coil L_1 to the lower terminal of coil L_3 , instead of to the common lead at the bottom of the diagram. This connection does not affect the alternating-current relations of Fig. 4, which are identical with those of Fig. 3.

40 In Figs. 1 to 4, the coupling between the circuit of coil L_3 and the main resonant circuit C_2 , L_2 , L_1 , or C_2 , L_2 , is effected through the coil L_1 , together with its electromagnetic 45 coupling to coil L_2 . However, it is possible to couple the circuit of L_3 directly with the main resonant circuit by coupling L_3 electromagnetically to L_2 . One method of accomplishing this is illustrated in Fig. 5, whose elements correspond to those of Fig. 1 and are 50 denoted by like reference characters. Fig. 5 also differs from Fig. 1 in isolating the primary system C_5 , L_1 , L_3 from the secondary system C_2 , L_2 in a way similar to that 55 shown in Fig. 4. As in the circuit arrangement of the preceding figures, L_1 of Fig. 5 should ordinarily have much fewer turns than L_2 ; and the circuit of L_3 , including L_1 and C_5 , should be made resonant at a frequency 60 somewhat lower than the lowest frequency within the range of C_2 . The proper relative polarities of coils L_1 and L_3 are as indicated, being such that the terminal of L_1 connected to one side of C_5 is of opposite 65 polarity to the terminal of L_3 connected to

the other side of C_5 ; the word "polarity" here referring to the polarity of the respective terminals when the coils are on open circuit. As before, there is in Fig. 5 a path from the plate to the filament which includes in series 70 the fixed condenser C_5 and the primary coil L_1 . With the relative polarities just stated, the voltages across L_1 and C_5 are additive, due to the fact that at frequencies higher than the resonant frequency of the circuit C_5 , L_3 the terminal voltage of L_3 is reversed with 75 respect to the voltage induced in L_3 by the current in L_2 . The voltage relations of Fig. 5 are thus similar to those of the preceding figures, although the mathematical equations 80 differ slightly in form.

As the self-inductance of coil L_3 in Fig. 5 should be made much greater than that of coil L_1 (which ordinarily has but few turns) it will make very little difference whether the lower terminal of L_3 is connected to the upper terminal of L_1 , as in Fig. 5, or to the lower terminal of L_1 , as in Fig. 6, so long as the correct polarity relations are maintained. The operation of Fig. 6 is qualitatively identical with that of Fig. 5 and can be made quantitatively identical by slight changes in the values of the circuit constants. As before, the circuit of coil L_3 , which is completed 90 through condenser C_5 , is resonant at a frequency lower, but not greatly lower, than the lowest frequency within the range of C_2 . Since the circuit of L_3 does not now include the coil L_1 , it is necessary to couple it to the secondary circuit C_2 , L_2 by electromagnetic 100 coupling between the coils L_3 and L_2 .

In cases where the natural capacities to ground of coil L_3 and condenser C_5 are objectionable, it may be desirable to interchange the order of this circuit and L_1 , in Fig. 6, giving the arrangement of Fig. 7. Except for the minor effects of these capacities to ground, the operation of Fig. 7 is identical with the operation of Fig. 6 if the relations of the parts are otherwise the same as 110 in Fig. 6.

The use of electromagnetic coupling between coils L_3 and L_2 in Figs. 5, 6 and 7 results in a more gradual variation with frequency of the voltage ratio E_2/E_1 and therefore of the performance, i. e., of the stability, sensitivity and selectivity. The coefficient of coupling between L_3 and L_2 should be neither very close nor very loose; a coupling of the order of 30% being satisfactory. It is to be understood that as many radio-frequency stages as required, similar to those herein described, may be connected in cascade—the output terminals of one stage connected to the input terminals of the next—in order to obtain the advantages of this invention in a multi-stage amplifier.

I claim:

1. In a radio amplifier stage including a vacuum tube having a filament, a grid and a 130

plate, an electric coupling system which comprises a main resonant circuit including as elements a secondary coil and a condenser, at least one of which is adjustable to tune the coupling system over a range in frequency, 5 a second circuit coupled to said resonant circuit, including a fixed self-inductance effectively in parallel with fixed capacity external to said main resonant circuit, whereby said 10 second circuit is resonant at a frequency lower than the lowest frequency within said range, a primary coil electromagnetically coupled to said secondary coil, and a path through said coupling system between said 15 plate and said filament including in series said primary coil and at least a portion of said fixed capacity, whereby in the operation of the amplifier stage there is developed in said main resonant circuit a resonant voltage whose ratio 20 to the voltage between the plate and the filament automatically rises when said adjustable element is adjusted for higher frequencies.

2. In a radio amplifier stage including a 25 vacuum tube having a filament, a grid and a plate, an electric coupling system which comprises a main resonant circuit including a fixed secondary coil and an adjustable condenser adapted to tune the coupling system 30 over a range in frequency, a circuit coupled to said resonant circuit, including a fixed self-inductance effectively in parallel with fixed capacity external to said main resonant circuit, whereby said second circuit is resonant 35 at a frequency lower, but not greatly lower, than the lowest frequency within said range, a primary coil electromagnetically coupled to said secondary coil and having few turns relatively thereto, and a path through 40 said coupling system between said plate and said filament including in series said primary coil and at least a portion of said fixed capacity, whereby in the operation of the amplifier stage there is developed in said main resonant circuit a resonant voltage high compared 45 with the voltage between the plate and the filament, and whereby the ratio of said resonant voltage to the voltage between the plate and the filament automatically rises 50 rapidly when said adjustable condenser is adjusted for higher frequencies.

3. In a radio amplifier stage including a 55 vacuum tube having a filament, a grid and a plate, an electric coupling system which comprises a main resonant circuit including a fixed secondary coil and an adjustable condenser adapted to tune the coupling system over a range in frequency, a fixed coil electromagnetically coupled to said secondary 60 coil, a circuit including said fixed coil and a fixed capacity effectively in parallel, said fixed capacity being external to said main resonant circuit, a primary coil electromagnetically coupled to said secondary coil, and a path through 65 said coupling system between

said plate and said filament including in series said fixed capacity and said primary coil, whereby in the operation of the amplifier stage there is developed in said resonant circuit a resonant voltage whose ratio to the voltage between the plate and the filament automatically rises when said adjustable condenser is adjusted for higher frequencies. 70

4. In a radio amplifier stage including a 75 vacuum tube having a filament, a grid and a plate, an electric coupling system which comprises a main resonant circuit including a fixed secondary coil and an adjustable condenser adapted to tune the coupling system over a range in frequency, a fixed coil electromagnetically coupled to said secondary coil, a circuit including said fixed coil and a fixed capacity effectively in parallel, and having a resonant frequency lower than the lowest frequency within said range, said fixed capacity 80 being external to said main resonant circuit, a primary coil electromagnetically coupled to said secondary coil, and a path through said coupling system between said plate and said filament including in series said fixed capacity 85 and said primary coil, whereby in the operation of the amplifier stage there is developed in said resonant circuit a resonant voltage whose ratio to the voltage between the plate and the filament automatically rises when 90 said adjustable condenser is adjusted for higher frequencies. 95

5. In a radio amplifier stage including a 100 vacuum tube having a filament, a grid and a plate, an electric coupling system which comprises a main resonant circuit including a fixed secondary coil and an adjustable condenser adapted to tune the coupling system over a range in frequency, a fixed coil electromagnetically coupled to said secondary coil, a circuit including said fixed coil and a fixed capacity effectively in parallel, said fixed capacity being external to said main resonant circuit, a primary coil electromagnetically coupled to said secondary coil, and a path 105 through said coupling system between said plate and said filament including in series said fixed capacity and said primary coil, said primary coil having such polarity relative to said fixed coil that the terminal of the primary coil connected to one side of said fixed capacity is of opposite open-circuit polarity to the terminal of the fixed coil connected to the other side of the fixed capacity, whereby in the operation of the amplifier stage there is developed in said resonant circuit a resonant voltage whose ratio to the voltage between the plate and the filament automatically rises when said adjustable condenser is adjusted for higher frequencies. 110

6. In a radio amplifier stage including a 115 vacuum tube having a filament, a grid and a plate, an electric coupling system which comprises a main resonant circuit including a fixed secondary coil and an adjustable con- 120

denser adapted to tune the coupling system over a range in frequency, a fixed coil electromagnetically coupled to said secondary coil, a circuit including said fixed coil and a fixed capacity effectively in parallel and having a resonant frequency lower than the lowest frequency within said range, said fixed capacity being external to said main resonant circuit, a primary coil electromagnetically coupled to said secondary coil, and a path through said coupling system between said plate and said filament including in series said fixed capacity and said primary coil, said primary coil having such polarity relative to said fixed coil that the voltages across said primary coil and said fixed capacity are additive, whereby in the operation of the amplifier stage there is developed in said resonant circuit a resonant voltage whose ratio to the voltage between the plate and the filament automatically rises when said adjustable condenser is adjusted for higher frequencies.

7. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a second circuit coupled to said resonant circuit including a fixed self-inductance effectively in parallel with fixed capacity external to said main resonant circuit, whereby said second circuit is resonant at a frequency lower, but not greatly lower, than the lowest frequency within said range, a circuit element having a substantially fixed voltage ratio relative to said main resonant circuit, and a path through said coupling system between said plate and said filament including in series said circuit element and at least a portion of said fixed capacity, whereby in the operation of the amplifier stage there is developed in said main resonant circuit a resonant voltage whose ratio to the voltage between the plate and the filament automatically rises when said adjustable element is adjusted for higher frequencies.

8. In a radio amplifier stage including a vacuum tube having a filament, a grid and a plate, an electric coupling system which comprises a main resonant circuit including as elements a coil and a condenser, at least one of which is adjustable to tune the coupling system over a range in frequency, a second circuit coupled to said resonant circuit including a fixed self-inductance effectively in parallel with fixed capacity external to said main resonant circuit, whereby said second circuit is resonant at a frequency lower, but not greatly lower, than the lowest frequency within said range, said fixed self-inductance being electromagnetically coupled to said resonant circuit, a circuit element having a substantially fixed voltage ratio relative

to said main resonant circuit, and a path through said coupling system between said plate and said filament including in series said circuit element and at least a portion of said fixed capacity, whereby in the operation of the amplifier stage there is developed in said main resonant circuit a resonant voltage whose ratio to the voltage between the plate and the filament automatically rises when said adjustable elements is adjusted for higher frequencies.

9. A radio-frequency coupling system having input terminals and comprising a main resonant circuit including as elements a coil and a condenser, at least one of which is adjustable to tune the coupling system over a range in frequency, a second circuit coupled to said resonant circuit including a fixed self-inductance effectively in parallel with fixed capacity external to said main resonant circuit, whereby said second circuit is resonant at a frequency lower, but not greatly lower, than the lowest frequency within said range, a circuit element having a substantially fixed voltage ratio relative to said main resonant circuit, and a path through said coupling system between said input terminals and including in series said circuit element and at least a portion of said fixed capacity, whereby there is developed in said main resonant circuit a resonant voltage whose ratio to the voltage between said terminals automatically rises when said adjustable element is adjusted for higher frequencies.

In testimony whereof I affix my signature.
CARL E. TRUBE.
